LUMINAIRE

Edmund L. Izzi, North Olmsted, Ohio, assignor to Westinghouse Electric Corporation, a corporation of Pennsylvania

Filed Oct. 31, 1963, Ser. No. 77,229

Term of patent 14 years

(Cl. D48—31)

FIG. 1 is a perspective view of a luminaire embodying my new design;

FIG. 2 is an elevational view thereof, the luminaire being symmetrical about its vertical axis as viewed therein; and

FIG. 3 is a top plan view thereof.

The broken line showing of a supporting bracket in FIGS. 1, 2 and 3 is for illustrative purposes only.

The dominant features of my design are indicated by the full lines of the drawings.

I claim:

The ornamental design for a luminaire, as shown and described.
